UNITED STATES PATENT OFFICE.

FRANK RUSSELL WHITE, OF WASHINGTON, DISTRICT OF COLUMBIA.

RAIL-FASTENING DEVICE.

1,097,831.

Specification of Letters Patent. Patented May 26, 1914.

Continuation in part of applications Serial No. 779,600, filed July 17, 1913, Serial No. 783,757, filed August 8, 1913, and Serial No. 786,745, filed August 25, 1913. This application filed September 16, 1913. Serial No. 790,036.

To all whom it may concern:

Be it known that I, FRANK RUSSELL WHITE, a citizen of the United States, residing at Washington, in the District of Columbia, have invented certain new and useful Improvements in Rail-Fastening Devices; and I do declare the following to be a full, clear, and exact description of the invention, such as will enable others skilled in the art to which it appertains to make and use the same.

This invention relates to railway ties and fasteners, and more especially to ties made of a composition, preferably reinforced concrete; and the object of the same is to produce a device of this character which is a combined tie and rail fastener, and to make the same of as few parts as possible, with but little opportunity for the entrance of moisture or for the automatic separation of parts under vibration and strain, and yet wherein the rail is supported on a wooden block in such way that the latter may be removed and replaced if it should become defective or rotted.

These objects are carried out by constructing the device in the manner hereinafter more fully described and claimed, and as shown in the drawings wherein—

Figure 1 is a longitudinal vertical section through a tie and rail fastener, showing the flange grips at the right end before and at the left end after they are canted and the keys applied; Fig. 2 is a plan view of the parts shown at the left end of Fig. 1, and Figs. 3 and 4 are cross sections on the lines 3—3 and 4—4 respectively of Fig. 1. Fig. 5 is a perspective detail of one of the flange grips, and Fig. 6 a similar detail of one of the pockets; Fig. 7 is an edge view and Fig. 8 a side view of one of the keys or fastening devices; Fig. 9 is a longitudinal sectional view on a reduced scale, showing the manner in which this tie is molded, one end of this view showing the mold as empty; Fig. 10 is a sectional detail of a modified construction employed for monorail tracks.

In the accompanying drawings I have used the letter R to show an ordinary railway rail having a web W and a base flange F, and the letter B to indicate a block preferably of wood forming a seat upon which said flange rests where the rail crosses my improved tie and is secured thereto by my

improved fastening means. The purpose of employing the block to support the rail is to afford a proper cushion so that the jar incidental to the passage of heavy trains will be communicated indirectly through the block, rather than directly to the concrete tie. The use of blocks of this kind is well known in the art.

Coming now to the details of the invention, Fig. 9 illustrates the manner in which this tie is made, and it will be observed that the tie is molded or cast in an inverted position. The mold M is of the proper dimensions to contain a completely finished tie, and it has a flat bottom b and a pair of narrow plugs p rising from and secured to said bottom near each end of the latter and with their inner faces spaced a little greater distance than the width of the wooden block B above referred to. In the act of molding one of my improved ties, the blocks B are first laid upon said base so that they extend completely across the interior of the mold M with their ends in contact with the sides of the mold but their sides out of contact with the adjacent faces of said plugs. Then the pockets and reinforcing bar are slipped into place with the inner walls of the pockets filling the spaces between the side faces of said blocks and the inner faces of said plugs while the extremities of said reinforce rest against the outer faces of said plugs and the latter therefore serve to hold all parts properly centered, next the cement to form the tie is poured in, and after the same has set the tie is removed from the mold and inverted for the reception of the rails and the grips and keys when the tie comes to be used. The construction is duplicated near each end of the tie, and I need therefore describe but one end.

There are two like pockets 2 for each block, one on either side thereof. As best seen in Fig. 6 each pocket consists of a sheet metal shell rectangular in cross section and open at its top 3 whereas its bottom 4 is closed, and as this bottom stands uppermost when the concrete is molded around it, no concrete enters the pocket. The inner wall 5 of the pocket rests against the side of the block B and is therefore preferably upright and flat, whereas the outer wall 6 is pierced with an opening 7 near its juncture with said bottom wall, the latter being by preference

continued outward into a lip 8 projecting slightly beyond the outer face of the outer wall 6 as shown.

The reinforcing bar 9 is of sufficient length to extend from rail to rail, and its tips 10 enter the openings 7 in the inner pockets. Near each end of the bar it has a branch 11 which is deflected downward from the straight body of the bar itself, and then carried outward at 12 under the block and turned upward into a hook 13, the tip of the latter entering the opening 7 in the outer pocket. In the finished article this engagement of the tips with the openings is useful for preventing the dislodgment of the pockets from the cement constituting the tie, and during the molding operation this engagement is useful for supporting the reinforcing bar when the parts are set up ready to receive the concrete. I make the hook of ample size so that it surrounds but does not stand too close to the lip 8. The latter prevents the dislodgment of the pocket from the finished article, but permits its removal if the block be first taken out.

The fastening device for the rail which I employ in conjunction with the parts above described, is best shown in detail in Fig. 5. It is by preference made of metal, and I call it a "flange grip" because it grips the flange F of the rail R. Being of substantially L-shape, its upper portion projects inwardly as a lip 20 from its upright body portion 21, the lip overlying the flange F as shown and the body portion projecting downward into the pocket 2. The thickness of the body portion is somewhat less than the corresponding dimension of the pocket 2, its width transverse to the length of the tie is slightly less than the internal width of said pocket, and its height is such that its lip 20 passes over the inner edge of the inner wall 5 of said pocket and rests on the rail-flange F as shown. This flange grip can be made of cheap casting, malleable iron or other suitable material; and I may say at this point that if the ends of the two rails R should meet above a tie of this character and should be connected by fish plates as usual, grips would be employed at this point whose lips 20 were slightly shorter and slightly thinner so that they would accommodate themselves to the thickness of the upright portion and the base leaf of the fish plate commonly used. It might be that the lateral dimension of the tie employed at this point would be increased so that it would be wider lengthwise of the rail. For holding the rail upon the block and therefore on the tie, the flange grip would not be useful, however, if it were not for some means by which it is locked within the pocket. Therefore I provide its body with a transverse hole 25 disposed opposite the tip 13 of the hook if it

be the inner grip. In order to produce the action described the lower face of the lip 20 is preferably obtuse to the inner face of the body portion 21 whereas their outer faces form substantially a right angle to each other; and downward through the lip 20 and along the beveled inner face of the body portion 21 is formed a key-seat 22 whose upper end is a hole and whose lower end is a channeled as indicated in Fig. 5, which upper end is intersected by a transverse perforation 23 for a purpose to appear below.

Coacting with the parts above described is a key or locking pin best seen in Figs. 7 and 8, its body 30 being rather thin and having straight parallel sides, and its upper end being headed as at 31. Just beneath the head said body is provided with a transverse perforation 33 adapted to align with the perforation 23 in the flange grip, and through the alining perforations is to be passed a retaining device 35 such as a nail whose tip can be bent, or a split pin or the like.

In the use of my invention, assuming that the tie proper has been made and properly disposed in the road bed, the rail R is laid across the same with the flange F resting over and centered upon the block B. One of the flange grips is then dropped into each pocket so that its lip 20 overlies the flange F and rests thereon at f, and its body 21 hangs by gravity close against said inner wall 5, but these parts stand at an obtuse angle to each other, the tip of the lip is now slightly elevated above the flange F as seen at the right of Fig. 1. By suitable means the grip is then canted or rocked over the point f so that the lip is brought down onto the rail-flange with its tip against the web at t, and the body portion 21 is thrown outward against the outer wall 6 at which time the hole 25 will pass over the tip 12 or 13 of the reinforcing bar so that all parts are locked together. The key or fastening pin is now inserted in the key-seat 22, its body 30 passing into place between the flange grip and the outer face of the inner wall 5 of the pocket so as to resist all strain thrown upon the flange grip and brace it clear to the upper end of the latter; and finally the retaining device 35 is passed through the perforations 23 and 33 to hold this key or locking pin in place.

In Fig. 10 is shown a slight modification adapted to be used on mono-rail tracks, in which case the tie 1' would be quite short and the body of the bar would be omitted or rather the horizontal portion 9' would have two hooks 13' whose tips project inward toward the single block embedded in the tie, into the pockets, and engage the holes in the two grips as above described.

It will not be necessary for the purposes of this specification to amplify details further.

If the block should become defective or rotted, it can be dislodged from or dug out of the composite tie without injuring the latter. In that case it will be necessary to first remove the retaining device 35; then remove the key, then with a suitable tool cant the grip back to its original position, and then lift it out of place. This releases the rail R which may be lifted off, and thereafter the block can be replaced at will.

Attention is directed to the fact that this device is useful without the necessity for employing spikes, screws, or bolts.

The present application is a continuation 15 of my former cases identified as follows, to wit: Serial Number 779600, filed July 17, 1913; Serial Number 783757, filed August 8, 1913; and 786745, filed August 25, 1913.

What is claimed as new is:

1. In a railway tie and fastener, the combination with a tie of reinforced concrete, blocks molded therein for supporting the rails, and open-topped pockets molded in said tie alongside said blocks; of two rail 25 fasteners for each block each consisting of a metallic member substantially L-shaped in side elevation, its body being perforated and standing within a pocket and its lip adapted to overlie the rail flange, and locking means 30 within said pocket engaging said perforation.

2. In a railway tie and fastener, the combination with a pair of blocks adapted to underlie the rails, and a metal reinforced 35 tie in which said blocks are embedded; of pockets molded in said tie alongside said blocks and having openings receiving the tips of said reinforce, and rail-fastening devices in said pockets.

3. In a railway tie and fastener, the combination with a pair of blocks adapted to underlie the rails, and a metal reinforced tie in which said blocks are embedded; of 45 pockets molded in said tie alongside said blocks and having openings receiving the tips of said reinforce, and outwardly projecting lips beneath said openings, rail fastening devices within said pockets, and keys in the latter for holding said devices in place 50 therein.

4. In a railway tie and fastener, the combination with a pair of blocks adapted to underlie the rails, and a metal reinforced tie in which said blocks are embedded, the 55 reinforce passing outwardly beneath the blocks and having hooked ends whose extremities turn inwardly; of pockets molded in said tie at the outer sides of said blocks and having openings receiving the tips of 60 said reinforce, and rail-fastening devices in said pockets.

5. In a railway tie and fastener, the combination with a pair of blocks adapted to underlie the rails, and a metal reinforce 65 passing outward beneath the blocks and

having hooked ends whose extremities turn inwardly; of pockets molded in said tie at the outer sides of said blocks and having openings receiving the tips of said reinforce and outwardly projecting lips beneath said 70 openings, rail fastening devices within said pockets; and keys in the latter for holding said devices in place therein.

6. The herein described railway tie consisting of a pair of parallel blocks adapted to underlie the rails, a reinforcing bar whose center stands at right angles to the length of said blocks, whose ends pass beneath them, and whose extremities are hooked inwardly toward them, and a cement 75 body molded around said bar and beneath and on both sides of said blocks.

7. In a railway tie and fastener, the combination with a pair of blocks adapted to underlie the rails, and a metal reinforced 80 tie in which said blocks are embedded, the reinforce passing outwardly beneath the blocks and having hooked ends whose extremities turn inwardly; of a pocket molded in said tie at the side of each block and having an opening, a flange grip having an upright body standing within the pocket and a transversely disposed lip at its upper end adapted to overlie the rail flange, and means for holding said body within the 85 pocket.

8. The herein described railway tie consisting of a pair of parallel blocks adapted to underlie the rails, pockets on opposite 90 sides of each block and having holes in their outer walls, L-shaped rail grips for said pockets whereof each has a lip overlying the rail-flange and a body provided with a hole standing opposite that in the pocket, a reinforcing bar whose tips project through the 95 holes in the pockets at the inner sides of the rails, each end thereof having a hook whose tip projects into the hole of the outermost pocket, and means for holding said grips with their holes engaging said tips.

9. The herein described railway tie consisting of a pair of parallel blocks adapted to underlie the rails, pockets on opposite sides of each block and having holes in their outer walls, L-shaped rail grips for said 100 pockets whereof each has a lip overlying the rail-flange and a body provided with a hole standing opposite that in the pocket, a reinforcing bar whose tips project through the 105 holes in the pockets at the inner sides of the rails, said bar near each end thereof passing under a block and having a hook whose tip projects into the hole of the outermost pocket, and keys in said pockets behind the grip-bodies for holding the latter in position to cause their holes to engage said tips.

10. The herein described railway tie and fastener consisting of a plastic tie, a block molded therein, pockets at opposite sides thereof, a metal reinforce molded in the tie 110

and having tips projecting into the outer sides of said pockets, in each of the latter a substantially L-shaped rail grip having a lip overlying the rail-flange and an upright body standing at an obtuse angle to the lip and pierced with an opening, and means within the pocket for holding said grip in position with its lip upon said rail flange and its opening engaging the tip of said re-

5 body standing at an obtuse angle to the lip and pierced with an opening, and means within the pocket for holding said grip in position with its lip upon said rail flange and its opening engaging the tip of said re-

10 inforce.

11. The herein described railway tie and fastener consisting of the tie body having a seat for the rail, pockets at opposite sides of said seat, a member within the tie-body having tips projecting into the outer sides of said pockets, a substantially L-shaped rail grip within each pocket whose lip is adapted to overlie the rail-flange and whose body stands obtuse to said lip and has an opening adapted to engage one of said tips, and a key in the pocket for holding the grip in active position.

12. In a rail-fastener, the combination with a pocket seated in a tie alongside a rail, and a member projecting through the outer wall of said pocket; of an L-shaped rail grip whose lip is adapted to overlie the rail-flange and whose body is provided with an opening to receive said member when the

grip is canted, said lip being provided with an upright key-seat running out along the back of said body portion, and a key removably inserted within said seat and against the inner wall of said pocket.

13. In a rail-fastener, the combination with a pocket seated in a tie alongside a rail, and a member projecting through the outer wall of said pocket; of an L-shaped rail grip whose lip is adapted to overlie the rail-flange and whose body is provided with an opening to receive said member when the grip is canted, said lip being provided with an upright key-seat running out along the back of said body portion and said lip portion being provided with a transverse perforation through said seat, a key inserted in said seat with its inner edge resting against the inner wall of said pocket and its body provided with a perforation adapted to align with that in the lip, and a fastening device passing through said aligned perforations.

In testimony whereof I have hereunto set my hand in presence of two subscribing witnesses.

FRANK RUSSELL WHITE.
